UNITED STATES PATENT OFFICE.

BENJAMIN F. FITCH, OF EVANSTON, ILLINOIS.

SUPPORT FOR TRAVELING CRANES AND SIMILAR STRUCTURES.

1,409,089.

Specification of Letters Patent.

Patented Mar. 7, 1922.

Application filed April 5, 1920. Serial No. 371,452.

To all whom it may concern:

Be it known that I, BENJAMIN F. FITCH, a citizen of the United States, residing at Evanston, in the county of Cook and State 5 of Illinois, have invented a certain new and useful Improvement in Supports for Traveling Cranes and Similar Structures, of which the following is a full, clear, and exact description, reference being had to the accompanying drawings.

This invention relates to supports for overhead traveling cranes, either when the wheel base is in a single plane or of the semi-gantry type wherein one leg of the 15 gantry travels upon a rail located on the floor within a building while the other leg is supported by an elevated rail.

Frequently the building construction is such that the wall does not possess sufficient 20 strength to support the live load of a crane. This is particularly true of freight stations and warehouses as they have ordinarily been constructed; because the entire load is usually carried by the floor, and the walls 25 need have only sufficient strength to support the roof.

One of the objects of this invention is to provide an effective and economical support adapted to carry an elevated rail for a crane 30 which may travel within a building. Another object is to provide a support that can be erected outside of a building and be adapted to support a rail inside of the building without materially altering the 35 structure of the wall.

I accomplish the above objects by means of fabricated columns supported on bases outside of the building but independent of the construction thereof. Secured to the 40 column I provide means which extend through an opening in the wall for supporting on the inside of the building a rail on which the crane may rest.

The above and other features will become 45 more apparent in the following description which relates to the drawings. The essential characteristics are summarized in the claims.

In the drawings Fig. 1 is a side elevation of my supporting means showing the relation of the column to the wall of a building; Fig. 2 is an elevation of a rail and supporting bracket, from a position within the building; Fig. 3 is a section of the base of the column taken on the line 3—3 as shown 50 in Fig. 1; Fig. 4 is a cross section through

the upper part of the column, taken in the line 4—4 shown in Fig. 1.

Describing the parts by the use of reference characters, in Fig. 1, 10 represents the outside wall of a building on the left side 60 of which is the warehouse or other building to which this invention may pertain. On the right side of this wall there may be a street or any thoroughfare which it is desirable not to obstruct by bulky supporting means. As shown, this wall is of brick construction but my invention is obviously adapted to any type of frame or fabricated metal construction.

Adjacent the wall, but on the outer portion thereof, is the supporting column 11, which is constructed independent of the wall 10, and preferably comprises a fabrication of angles 12 with lattice work 13. This column is preferably constructed in a tapered form, having the base wider than the top. The column 11 has rigidly secured to the lower portion, base plates 14 which may be rigidly secured to an independent concrete foundation 15 through anchor bolts 16. 80 These base plates may be rolled structural shapes or castings as desired. They serve to give the column an independent supporting means and are conveniently constructed of sufficient size to overcome any tensile or 85 shearing forces resulting from any load resting on the top of the column.

Secured to the top portion of the column 11 and extending through the wall 10 is the bracket 17. This member is preferably a 90 steel casting of an L-shaped form comprising a vertical leg 18 adjacent the inner face of the column and rigidly secured thereto, with a horizontal leg 19 which serves as a support for the rail 21. To brace the bracket I provide a web 20 as shown in Fig. 4. This bracket may be secured to the column 11 by the bolts 22 which extend through the column, substantially as shown.

To prevent buckling of the column at the 100 point of connection, of the bracket, I prefer to provide spacing members 23, which are substantially sleeves that embrace the bolts and have their ends abut the inner faces of the column. Obviously any strain which 105 might be imparted to the column through tightening the nuts in bolts 22 will be partly compensated for by these sleeves.

Holes may be drilled in the angles 12 at various heights on the column so that the 110

2
bracket 17 may be adjusted for different buildings or have various heights in the same building. The purpose of this adjustment is to provide universal supports as near as is practicable for any shape or size of building.

10 The rail 21 may be secured to the bracket 17 by clips 24 which are substantially U-shaped members so arranged that the upper arm thereof rests upon the rail, while the lower arm is underneath the cross arm 24 of the bracket. On the other side of the rail there may be another clip-like member as shown at 25 in Fig. 1. These two members may be secured together by a bolt 26 which passes through the bracket arm.

15 When installing the supports, concrete bases may be constructed adjacent to the wall but independent thereof. The universal columns may then be set in place and the brackets rigidly adjusted thereon for supporting the rails. Obviously, if the contour of the ground is such, that it is necessary to use different heights of columns to 20 maintain a uniform height of the supporting rail, above the ground, then it is only necessary, with my invention, to so position the bracket through holes in the column that this desired height can be readily maintained.

30 It will be seen that I have provided a support that is light in weight, strong, durable, capable of being cheaply manufactured and adapted for ready application for existing structures. Being composed principally of rolled structural members my columns may be fabricated of desired length from material kept in stock or supplied in quantities.

40 Having thus described my invention I claim:

1. In a rail supporting device the combination with a building wall having an opening therein of a column adjacent thereto and in the outside thereof, a base for said column, a bracket on said column extending from one side of said wall to the other through the opening, and means on said bracket for supporting a rail.

45 2. In a device of the character described, the combination with a building wall, having an opening therein of a column adjacent one side of the building wall, base plates on said column adapted to be secured to foundations independent of said walls, and a bracket adjustably secured to said column for supporting a rail on opposite side of

said wall, said bracket being in close fitting engagement into the opening in the wall.

3. In a rail supporting device, a column 60 comprising a fabrication of angle members adapted to be positioned adjacent a building wall and in the outside thereof and supported independent thereof, a bracket adjustably secured to said column, bolts 65 adapted to secure said bracket to said column, and a U-shaped clip carried by said bracket and adapted to secure a rail.

4. In a rail supporting device, a column 70 comprising a fabrication of angle members, a bracket adjustably secured to the side of said column, bolts adapted to secure said bracket to said column, sleeves embracing said bolts and extending between facing flanges of the angle members, said sleeves 75 being substantially of a length equal to the distance between the opposite angle members at the point where said bracket is secured, and means on said bracket adapted to secure a rail.

5. The combination with a column comprising angle members positioned adjacent a wall and on the outside thereof, of a base 80 adapted to support said column independent of said wall, said angle members being positioned to form the shape of an I-beam, lattice work adapted to form the web portion of said I-beam, a bracket adjustably secured to said column by bolts and adapted to extend through an opening in said wall, a rail 90 carried by the bracket, a flat clip on one side of the base flange of the rail, a hook-shaped clip abutting the other side of the base flange and extending under the bracket, and means passing through each clip for securing them to the bracket.

6. The combination with a wall, having an opening therein of a column comprising angle members positioned adjacent to the wall, of a base adapted to support said 100 column independent of said wall, an L-shaped bracket adjustably secured to the side of said column adjacent the wall and extending through an opening in said wall, one arm of the bracket substantially closing 105 the opening in the wall, bolts securing the bracket to the column, sleeves embracing said bolts, a rail resting on the inner end of said bracket, and a clip adapted to secure the rail to the bracket.

110 In testimony whereof, I hereunto affix my signature.

BENJAMIN F. FITCH.
